(57) CLAIM

The ornamental design for a nail polish container holder, as shown and described.

DESCRIPTION

FIG. 1 is a top, front, and left-side perspective view of a nail polish container holder showing my new design;
 FIG. 2 is bottom, back and left-side perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines in the drawings are for the purpose of illustrating portions of the nail polish container holder that form no part of the claimed design.

1 Claim, 8 Drawing Sheets
